UNITED STATES PATENT OFFICE.

ANNETTE HARBIDGE, OF LIVERPOOL, ENGLAND, ASSIGNOR TO HENRY SAMUEL MORTON, OF HOBOKEN, NEW JERSEY.

CORSET.

SPECIFICATION forming part of Letters Patent No. 783,579, dated February 28, 1905.

Application filed October 29, 1904. Serial No. 230,451.

To all whom it may concern:

Be it known that I, ANNETTE HARBIDGE, a citizen of the United States of America, residing temporarily at Derwent Lodge, Wavertree, Liverpool, England, have invented certain new and useful Improvements in Corsets, of which the following is a specification illustrated by the accompanying drawings.

The form of corset most commonly in use 10 at the present time is made in two halves, each extending from the middle of the front around to the middle of the back. These halves are fastened in the front by means of a series 15 of hooks and clasps and in the back by means of lacing passing through a series of eyes or rings in the edges of the halves. In this form of corset it has been found difficult to conform it to the figure of the wearer without unduly pressing down upon the delicate organs and 20 upon the digestive organs, thereby producing discomfort and injury thereto. This form of corset also presses the bust up in an unnatural position, and by pressing firmly down upon the back is apt to injure the kidneys.

25 The object of this invention is to obviate these and other objections by constructing the corset in such a manner that no undue pressure occurs and the corset acts as a supporter to the busts and to the abdomen and is far 30 more hygienic than the corsets at present in use.

In the drawings, Figure 1 is a front elevation of the corset as used, shown fastened; Fig. 2, a rear elevation of the same; Fig. 3, a 35 view of a portion of the corset, showing the means for fastening the bust-supporters. Fig. 4 is a side view of the corset shown closed.

The corset is composed of one continuous portion *a*, which reaches from the opening *b* 40 across the back of the wearer to the opening *c*. In the center of the front are the two triangular portions *d* and *e*. These portions *d* and *e* are connected together by means of a series of suitable clasps and hooks, as shown, 45 making a firm connection between the two parts. The portions *d* and *e* are connected each with the corresponding part of the portion *a* by means of a series of lacings. The vertical edges of each of the portions *a*, *d*,

and *e* are provided with busks, of metal or 50 other suitable material, which are sewed or otherwise fastened to the body of the corset along the edges and extend the entire length of each edge. The busks on the adjoining edges of the portions *d* and *e* are provided one 55 with hooks and the other with corresponding clasps, while the busks on the edges of the openings *b* and *c* are provided with eyes or rings adapted to receive the lacing which connects the two edges. The manner of fastening 60 the two front portions together does not differ in any way from the manner now in use on other forms of corsets; but it is to be observed that while the present form of corset laces up the back in this device there are two 65 lines of lacing in the front, and the back is continuous.

At the point above the middle of each side nearly underneath the arms of the wearer there are fastened in any suitable manner two 70 pieces *f* and *g* of silk or ribbon, which are of sufficient length that when brought together in the front they may be tied in the form of a bow or knot. These pieces are each provided with a strip *h* of whalebone or other suitable 75 material, which extends the breadth of the pieces and is sewed on their inner surface.

On the lower portion of the corset are the pieces *k*, *k*, which are made of strong webbing and substantially cover the abdomen of the 80 wearer. These pieces are securely fastened into the corset and to the busks and are designed to be used as a support for the abdomen and also as a substitute for the belt which is worn after an operation for appendicitis. 85

On reference to Fig. 2 it will be seen that the bones in the back are comparatively short, giving a reasonable amount of support without pressing on the kidneys, while the busks extending far down in front will hold the abdomen in place without producing discomfort.

The portions *d* and *e* for the average figure are made the same, the differences in size being allowed on the portion *a*.

It will be seen that this corset possesses the 95 advantages of supporting the delicate organs by means of the lacing extending far down in front, fitting comfortably over the hips, sup-

porting the busts in a natural position, the boning being firm and not hard and the short bones in the back giving the needed support without undue pressure. It is also to be observed that in this form of corset a line drawn from beneath the armhole of the wearer to the bottom, where the two ends are hooked together, will be longer in this corset than they will be in other forms now in use, and consequently there will be less tendency for the corset to ride up away from the abdomen, and instead there will be a tendency to keep the corset in place, even when the wearer indulges in active exercise.

Without enumerating the many modifications which may be made of this invention, what I desire to secure by Letters Patent is the following claim:

A corset, open at the center of the front and at either side of said center opening and pro-

vided on the edges of said openings with busks, a series of clasps and hooks adapted to close said opening, busks provided in the edges of the side openings, a series of lacing devices adapted to substantially close the said openings and conform the corset to the figure of the wearer, abdominal portions made of elastic material and bust-supporters attached to the upper portion of the corset at the middle of each side and adapted to be tied in the center of the front, said bust-supporters being provided with bones to enable them to be retained in the desired position, substantially as described and set forth.

Signed this 27th day of October, 1904, at 35 New York, N. Y.

ANNETTE HARBIDGE.
